H. P. ROBERTS

BOTTLE CAP

Filed Jan. 22, 1923

Inventor:
Henry P. Roberts,
by Walter E. Lombard,
Atty.

UNITED STATES PATENT OFFICE.

HENRY P. ROBERTS, OF BOSTON, MASSACHUSETTS, ASSIGNOR OF ONE-HALF TO
GEORGE M. PROCTOR, OF BOSTON, MASSACHUSETTS.

BOTTLE CAP.

Application filed January 22, 1923. Serial No. 614,122.

To all whom it may concern:

Be it known that I, HENRY P. ROBERTS, a citizen of the United States of America, and a resident of Boston, in the county of 5 Suffolk and State of Massachusetts, have invented certain new and useful Improvements in Bottle Caps, of which the following is a specification.

This invention relates to bottles caps and 10 has for its object the provision of means whereby a bottle may be hermetically sealed.

The invention consists of a cap having inturned ears adapted to engage a flange on the neck of a bottle, combined with 15 means for forcing said ears into gripping contact with said neck.

The invention further consists of a cap provided with a packing member and having a non-revolvable threaded stem extending 20 through a bar having inturned arms for forcing said disk into gripping contact with a flange on the neck of a bottle, said stem having an adjusting nut by which the cap may be forced against the end of the bottle.

25 The invention further consists in certain novel features of construction and arrangement of parts which will be understood readily by reference to the description of the drawings and to the claims to be hereinafter given.

30 For the purpose of illustrating the invention, one preferred form thereof is shown in the drawings, this form having been found to give satisfactory and reliable results, although it is to be understood that the various instrumentalities of which the invention consists can be variously arranged and organized, and that the invention is not limited to the precise arrangement and 35 organization of the instrumentalities as herein shown and described, except as required by the scope of the appended claims.

40 Of the drawings:

45 Figure 1 represents a front elevation of the upper end of a bottle and having applied thereto a bottle cap embodying the principles of the present invention.

Figure 2 represents a plan of the same.

50 Figure 3 represents a side elevation of the same.

Figure 4 represents a vertical section through the bottle closing disk, on line 4, 4 on Fig. 1.

Figure 5 represents a plan of the blank from which the disk supporting bar is 55 formed.

Figure 6 represents an inverted plan of the bottle closing disk with the packing member removed, and

Figure 7 represents a vertical section of 60 same on line 7, 7 on Fig. 6.

Similiar characters indicate like parts throughout the several figures of the drawings.

In the drawings, 10 is a bar having 65 downwardly extending arms 11, the lower ends of which are inturned as indicated at 12, these inturned ends 12 being adapted to extend below a flange 13 on the neck 14 of a bottle.

The bar 10 has a cylindrical opening 15 therein through which extends the threaded stem 16 projecting upwardly from a cup-shaped disk 17. This cup-shaped disk 17 has a cylindrical opening 18 centrally disposed therein, in which is positioned the threaded stem 16, the lower end of which is provided with a flat-sided head 19 positioned in a recess 20 formed in the under side of the cup-shaped disk 17.

75 Positioned within the cup-shaped disk 17 is a resilient packing member 21 which is adapted to rest upon the upper end of the neck 14 of the bottle.

80 The cup-shaped disk 17 is provided with 85 oppositely disposed ears 22, the out-turned lower ends of which are positioned in open-ended slots 23 formed in the inturned ends 12 of the arms 11. By thus positioning the ears 22 in the slots 23, the bar 10 and the disk 17 are prevented from rotating relatively to each other.

85 The outer end of the threaded stem 16 has an adjusting nut 24 mounted thereon, the under face of which bears against the 90 upper face of the bar 10. When the disk 17 is positioned upon the end of the neck 14 of a bottle, with the ears 22 engaging the under portion of the flange 13, it is obvious that when the nut 24 is rotated clockwise 95 about the axis of the stem 16, the bar 10 will be forced downwardly, thereby causing the ears 22 to be moved toward each other into gripping contact with the neck of the bottle. Further rotation of the nut 24 will 100 cause the disk 17 to be forced against the 105

upper end of the neck 14 and compress the packing member 21, thereby hermetically sealing the bottle.

All rotary movement of the bar 10 and disk 17 is prevented by the friction of the packing member 21 in engagement with the upper end of the neck 14 of the bottle.

When it is desired to remove the cap from the bottle, the nut 24 is rotated contra-clockwise and this movement will cause the pressure of the arms 12 on the ears 22 to be removed. The disk 17 may then be removed from contact with the end of the bottle by snapping the ears 22 over the flange 13 on the bottle neck 14.

This makes a very simple device to be used on various forms of bottles to hermetically close the same until it is desired to secure access to the contents of the bottle.

It is believed that the operation and many advantages of the invention will be understood readily without further description.

Having thus described my invention, I claim:

1. A bottle cap consisting of a non-revoluble disk having oppositely disposed downwardly extending ears adapted to engage a flange on the neck of a bottle; a bar having arms engaging the outer faces of said ears; and means for adjusting said bar toward said disk to cause said ears to move toward each other and grip said neck.

2. A bottle cap consisting of a bar having oppositely disposed arms; a non-revoluble disk provided with a stem extending through an opening in said bar and having downwardly extending ears adapted to be forced toward each other by said arms; and means for adjusting said bar toward and from said disk.

3. A bottle cap consisting of a non-revoluble disk provided with a threaded stem and having downwardly extending ears adapted to engage a flange on the neck of a bottle; a bar provided with an opening through which said stem extends and having oppositely disposed inturned arms adapted to force said ears into gripping contact with said neck; and an adjusting nut on the projecting end of said stem.

4. A bottle cap consisting of a non-revoluble disk having oppositely disposed ears adapted to engage a flange on the neck of a bottle and provided with a threaded stem; a bar provided with an opening through which said stem extends and having oppositely disposed inturned arms adapted to force said ears into gripping contact with

said neck, said arms having open-ended slots to receive said ears; and an adjusting nut on the projecting end of said stem.

5. A bottle cap consisting of a non-revoluble disk provided with a threaded stem and having downwardly extending ears adapted to engage a flange on the neck of a bottle; a bar having an opening to receive said stem and provided with arms adapted to force said ears into gripping contact with said neck; means for preventing the rotation of said bar relatively to said disk; and an adjusting nut on the projecting end of said stem.

6. A bottle cap consisting of a non-revoluble cup-shaped disk provided with a threaded stem and having downwardly extending ears adapted to engage a flange on the neck of a bottle; a resilient packing member in said cup-shaped disk; a bar having an opening to receive said stem and provided with arms adapted to force said ears into gripping contact with said neck; means for preventing the rotation of said bar relatively to said disk; and an adjusting nut on the projecting end of said stem.

7. A bottle cap consisting of a non-revoluble disk having a flat-sided central opening therein and provided with downwardly extending ears adapted to engage a flange on the neck of a bottle; a headed member having a flat-sided portion positioned in said opening and provided with a threaded stem; a bar having an opening to receive said stem and provided with arms adapted to force said ears into gripping contact with said neck; and an adjusting nut on said threaded stem.

8. A bottle cap consisting of a non-revoluble disk having a flat-sided central opening therein and provided with downwardly extending ears adapted to engage a flange on the neck of a bottle; a headed member having a flat-sided portion positioned in said opening and provided with a threaded stem; a bar having an opening to receive said stem and provided with arms adapted to force said ears into gripping contact with said neck; an adjusting nut on the projecting end of said stem; and a packing member secured to the bottom of said disk.

Signed by me at 746 Old South Bldg., Boston, Mass., this 17th day of January, 1923.

HENRY P. ROBERTS.
